(57) **CLAIM**

The ornamental design for a spanner tool, as shown and described.

DESCRIPTION

FIG. 1 is a perspective view of a spanner tool, showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and

FIG. 7 is a bottom plan view thereof.

FIG. 8 is a perspective view showing an application of the present invention.

FIG. 9 is a perspective view showing a second application of the present invention; and,

FIG. 10 is a perspective view showing a third application of the present invention.

The broken line showing of open and closed end wrench heads is for illustrative purposes only and forms no part of the claimed design.
